EUGÈNE SCHNEIDER, OF PARIS, FRANCE, ASSIGNOR TO SCHNEIDER & CIE., OF PARIS, FRANCE, A LIMITED JOINT-STOCK COMPANY OF FRANCE.

COMPRESSED-AIR RECUPERATOR FOR GUNS.

1,421,576.

Specification of Letters Patent.

Patented July 4, 1922.

Application filed December 28, 1920. Serial No. 433,660.

To all whom it may concern:

Be it known that I, EUGÈNE SCHNEIDER, citizen of the Republic of France, resident of Paris, France, have invented new and 5 useful Improvements in Compressed-Air Recuperators for Guns, which invention is fully set forth in the following specification.

This invention has for its object to provide an improved compressed air recuperator for guns, of the type comprising an air reservoir fixed to the stationary part of the gun or to the recoiling part, and wherein a piston is adapted to work having its rod 10 attached to the said recoiling part or to the said stationary part respectively.

The improved recuperator is characterized essentially by the feature that the air is kept confined therein between the inner 20 wall of the reservoir and the wall of the piston rod by means of pistons comprising annular hydraulic joints having movable heads, arranged in the annular space comprised between the said reservoir and the 25 piston rod. According to this invention these joints are also so constructed that the state of the charge of liquid can be ascertained at any time without taking the apparatus to pieces.

Various constructional forms of this invention are illustrated by way of example in the accompanying drawings in which:—

Figs. 1 and 1^a are longitudinal vertical sections of one example of the application 35 of the improved recuperator; the section being taken on the line 1—1 of Figs. 2 and 3 which are respectively cross sections on the lines 2—2 and 3—3 of Figs. 1 and 1^a respectively.

Fig. 4 is a partial elevation of a detail.

Figs. 5 and 6 are diagrammatic sections illustrating the application of the invention to a gun with differential recoil.

Figs. 7 and 7^a are vertical longitudinal 45 sections of another constructional form of this invention.

In these figures:—A is a reservoir which in the examples shown, is assumed to be attached to the stationary part of the gun. 50 This reservoir is formed as an annulus around a rod B which is fixed to the recoiling part, for instance the slide C. The compressed air is confined between the inner wall a of the reservoir A and the wall of 55 the rod B which latter may have a recess

B¹ communicating with the annular space A¹ through a hole b. As a matter of fact the air is confined in the space A¹—B¹ by a pair of pistons slidably mounted in spaced relation on the rod B and comprising two 60 hydraulic joints having movable heads, the joints being arranged in the annular space between the wall a and the wall of the rod B. Each of these joints comprises an inner disc (D, D¹ respectively) constituting the 65 movable head, that serves as an abutment on its inner face for joint packings d d¹ and on its outer surface for packings e, e¹, respectively.

The packings d, consisting for instance, 70 of cupped leathers, are kept tightened by means of rings F screwed on a collar f formed as a projection on the disc D.

The packings e are arranged inside and outside an annular member (E, E¹ respectively) projecting externally from the disc (D, D¹). 75

The hydraulic joint is formed between the packing e and packings g that close the annular spaces comprised between the inner 80 wall of the said annular member and the outer wall of the rod B.

Rings H, H' press these packings g, g' against an abutment ring (I, I¹ respectively) which bears normally with its outer end 85 against the corresponding end of the reservoir A. The abutment ring I is formed with a recess i that serves as a guide for the annular member E; the said recess i communicates with the atmosphere by way of 90 passages J through which extend extensions K projecting from the annular member E.

The charging of the recuperator with air is effected through a passage b¹ that is normally closed by a plug B². The charging 95 with liquid, of the hydraulic joint of the left hand movable head is effected through a passage b² formed in the rod B and normally closed by a plug B³. The charging of the right hand hydraulic joint is effected 100 through the passage a¹ which is pierced in the wall of the reservoir A and is normally closed by a plug A². The extensions K K¹ are made of such length as will make their 105 ends flush with the corresponding end of the reservoir A, when, the reservoir having been charged with air, the liquid fills suitably the space between the packings e and g for one of the joints, and e¹, g¹, for the other joint. Any loss of liquid would be indicated 110

by the projecting of the extensions and would notify the gun servers that the joints require recharging.

The liquid contained in chambers L, L¹, is subjected to the pressure that is transmitted to it by the discs D, D¹. However the pressure exerted upon the inner faces of the discs is transmitted to the outer surface, which latter is diminished by the sections of the respective annular members E and E¹, with the result that the packings e e¹ are subjected to a higher pressure from the side of the liquid. This fact prevents completely any leakage of the air.

In the example shown in Figs. 1 to 4, the air confined in A¹—B¹ is compressed by the recoil owing to the fact that the rod B, draws with it by means of its shoulder B⁴, the abutment ring I, and through the latter the hydraulic joint of the left hand movable head. On the completion of the recoil the return of the gun into battery position, is effected by the action of the expansion of the air that was compressed by the recoil in A¹—B¹.

When the improved recuperator is applied to a gun having a differential recoil, the slide C is coupled up for loading the projectile into the gun breech during the return of the gun into battery position; then the slide is uncoupled again, and the gun is fired; a portion of the momentum of the mass returning into battery position being utilized to impart velocity to the whole of the recoiling mass, thus finally reducing the force required for braking. In the case of a misfire the recoiling mass is thrown forwards with an excessive force which necessitates the use of a shock-absorbing brake.

Fig. 5 shows diagrammatically in full lines the position of the parts of the recuperator when the slide C, with the whole of the recoiling mass, is coupled-up in the return into battery position for loading the projectile into the gun breech. After this loading, the return of the gun into battery position is completed, and the gun is fired, the parts having taken up normally the position indicated in dot-and-dash lines in the same Fig. 5.

The recoil takes place as soon as the gun is fired. In the case of a misfire the movable portion, instead of recoiling, tends on the contrary to continue its forward movement. In such a case the abutment disc I¹ with the right hand situated hydraulic joint, is carried along towards the left as shown in Fig. 6, which movement is possible so long as the slide C and the reservoir A do not meet. Such meeting however is not possible because the air confined between the two hydraulic joints is compressed and acts as a shock-absorber.

It will thus be perceived that the recuperator, applied to the gun having a differential recoil, acts as a shock-absorber or

brake in the case of mis-fire, that is to say reversely to what takes place with the usual recuperators.

Fig. 7 illustrates a modification wherein the compressed air is confined between the end of a reservoir A, the end B¹ of a hollow plunger B, and an annular hydraulic joint with a movable head D—E—F arranged between the inner wall α of the reservoir and the outer wall of the plunger. The compression of the air in this case is due to the entry of the plunger into the reservoir A during the recoil. The charging with air takes place through a passage α^2 of the reservoir that is normally closed by a plug. The charging with the liquid takes place through another passage α^1 of the said reservoir that is normally closed by a plug A².

Having now particularly described and ascertained the nature of my said invention and in what manner the same is to be performed, I declare that what I claim is—

1. In a recuperator for guns having a stationary part and a movable part, a reservoir attached to one of said parts, a hollow rod attached to the other of said parts and extending within said reservoir, said hollow rod having communication with said reservoir and being adapted to receive a fluid under compression, and means confining the fluid between the inner surface of the reservoir and the wall of said hollow rod, said means comprising a pair of packing members slidably mounted in spaced relation on said rod, one of the packing members being movable with said rod to compress the fluid on rearward movement of the gun and the other packing member being movable with said rod to compress the fluid on forward movement of the gun.

2. In a compressed air recuperator for guns having a stationary part and a movable part, a reservoir attached to one of said parts, a hollow rod attached to the other of said parts and extending within said reservoir, said rod having communication with the interior of the reservoir and being adapted to receive compressed air, and means surrounding said hollow rod and confining the compressed air between the inner surface of the reservoir and the wall of the hollow rod, said means comprising hydraulic packing of the movable head type, a movable head of said packing being provided with an extension normally projecting from the reservoir for indicating the volume of liquid within the packing.

3. In a recuperator for guns having a stationary part and a movable part, a reservoir attached to one of said parts, a hollow rod attached to the other of said parts and extending within said reservoir, said hollow rod having communication with the interior of the reservoir and being adapted

to receive a fluid under compression, and means confining the fluid between the inner surface of the reservoir and the wall of the hollow rod, said means comprising a pair 5 of hydraulic packing units of the movable head type slidably mounted on said hollow rod, and arranged in the annular space between the reservoir and the said hollow rod, one of said hydraulic packing units being 10 movable with said hollow rod to compress the fluid on rearward movement of the gun and the other of said packing units being movable with said rod to compress the fluid on forward movement of the gun. 15

4. In a recuperator for guns having a stationary part and a movable part, a reservoir attached to one of said parts, a hollow rod attached to the other of said parts and extending within said reservoir, said hollow rod having communication with the interior 20 of the reservoir, means providing for charging of the reservoir and hollow rod with a fluid hydraulic packing of the movable head type surrounding said hollow rod and confining the fluid between the inner surface of 25 the reservoir and the wall of the hollow rod, said hydraulic packing including a member rigidly connected with the wall of said reservoir, the movable head of the hydraulic packing unit being provided with extensions projecting beyond the reservoir for indicating 30 the volume of liquid within said packing unit.

5. In a recuperator for guns having a stationary part and a movable part, a reservoir 40 attached to one of said parts, a hollow piston rod attached to the other of said parts and extending within said reservoir, said piston rod being adapted to receive a fluid under compression and communicating with said 45 reservoir throughout the recoil and running out of the gun, and means for confining a fluid between the inner surface of the reservoir and the wall of the piston rod, said means comprising a pair of spaced pistons 50 slidably mounted on the piston rod and arranged in the annular space between the reservoir and the piston rod.

6. In a recuperator for guns having a stationary part and a movable part, a reservoir 55 attached to one of said parts, a hollow rod attached to the other of said parts, and extending within said reservoir, said hollow rod being adapted to receive a fluid under compression and communicating with said 60 reservoir throughout the recoil and running out of the gun, and means for confining the fluid within the reservoir and the hollow rod, said means comprising a pair of spaced packing members 65 slidably mounted on said hollow rod, and arranged in the annular

space between the reservoir and the hollow rod, one of the packing members being movable with said rod to compress the fluid on rearward movement of the gun and the other packing member being movable with said rod to compress the fluid on forward movement of the gun. 70

7. In a recuperator for guns having a stationary part and a movable part, a reservoir attached to one of said parts, a hollow rod 75 attached to the other of said parts and extending within said reservoir, said hollow rod having communication with said reservoir and being adapted to receive a fluid under compression, and means carried by the 80 hollow rod for confining the fluid within said rod and the reservoir, said means comprising hydraulic packing of the movable head type, a movable head of said packing being provided with an extension normally 85 projecting from the reservoir for indicating the volume of liquid within the packing.

8. In a recuperator for guns having a stationary part and a movable part, a reservoir attached to one of said parts, a piston rod 90 attached to the other of said parts and extending within said reservoir, and means for confining a fluid between surfaces of the reservoir and said piston rod, said means comprising a pair of spaced pistons slidably 95 mounted on the piston rod and arranged in the annular space between the reservoir and said rod.

9. In a recuperator for guns having a stationary part and a movable part, a reservoir attached to one of said parts, a piston rod 100 attached to the other of said parts and extending within said reservoir, and means for confining a fluid between surfaces of the reservoir and said piston rod during the 105 recoil and running out of the gun, said means comprising a pair of spaced pistons slidably mounted on the piston rod and arranged within the reservoir, one of said pistons being movable with the piston rod to compress the fluid on recoil of the gun and the other of said pistons being movable with the piston rod to compress the fluid on running out of the gun. 110

10. In a recuperator for guns having a stationary part and a movable part, a reservoir attached to one of said parts, a piston rod 115 attached to the other of said parts and extending within said reservoir, and means for confining a fluid between surfaces of the 120 reservoir and said piston rod, said means comprising a pair of spaced pistons slidably mounted on the piston rod, each of said pistons comprising a hydraulic packing unit of the movable head type. 125

11. In a recuperator for guns having a stationary part and a movable part, a reservoir attached to one of said parts, a hollow piston rod attached to the other of said parts, and extending within said reservoir, said hollow 130

piston rod being adapted to receive a fluid under compression and communicating with, said reservoir throughout the recoil and running out of the gun, means for confining the fluid between the inner surface of the reservoir and the wall of the hollow piston rod, said means comprising a pair of spaced hydraulic packing members slidably mounted on the piston rod and arranged in the annular space between the reservoir and said rod, and means on said packing members

normally extending beyond the reservoir for indicating the volume of liquid in said members.

Dated this 23rd day of November 1920. ¹⁵
In testimony whereof I have signed this specification.
